UNITED STATES PATENT OFFICE.

RICHARD J. FREEMAN, OF OVERBROOK, PENNSYLVANIA, ASSIGNOR TO PIONEER SUSPENDER COMPANY, A CORPORATION OF PENNSYLVANIA.

DESIGN FOR A GARTER.

43,105.

Specification for Design.

Patented Oct. 8, 1912.

Application filed June 29, 1910. Serial No. 569,605. Term of patent 14 years.

To all whom it may concern:

Be it known that I, RICHARD J. FREEMAN, a citizen of the United States, residing at Overbrook, in the county of Philadelphia, State of Pennsylvania, have invented a new, original, and ornamental Design for Garters, of which the following is a specification, reference being had to the accompanying drawing, forming part thereof.

The figure is a view in perspective of a garter, showing my new design which comprises the employment with the leg band

and clasp, of the triangular connecting structure therebetween comprising a flat band folded upon itself and having a permanent or constant triangular formation.

I claim:

The ornamental design for a garter, as shown and described.

RICHARD J. FREEMAN.
